UNITED STATES PATENT OFFICE.

HERMAN C. SPINDLER, OF AKRON, OHIO, ASSIGNOR TO WILLIAM C. MCCOY, OF AKRON, OHIO.

AUTOMATIC PENCIL.

Application filed June 7, 1921. Serial No. 475,711.

My invention relates to automatic pencils and it particularly appertains to pencils in which the marking leads are operatively advanced by manipulating relatively movable parts of the pencils.

The primary object of my invention is to provide an automatic pencil having greatly improved operating characteristics and large operating parts that are particularly rugged and strong. My improved pencil is adapted to carry an increased reserve supply of leads, it may be manufactured at reduced cost, and readily lend itself to the design of the customary large size of man's pencil or the reduced size of pencil for ladies without impairing its advantageous operating characteristics or ruggedness of structure.

Other primary and ancillary objects and advantages to be derived from practicing my invention will be apparent from a study of the description and the accompanying drawing in which:

Fig. 1 is a longitudinal sectional view of my improved pencil with certain parts broken away and other parts shown in elevation for clearness of illustration;

Fig. 2 is a detailed perspective view of the operating mechanism for advancing the lead projecting plunger; and

Fig. 3 is a detailed sectional view of the pencil taken substantially on the line 3—3 of Fig. 1.

Figure 4 is a detailed longitudinal sectional view of the lead receiving tube and associated collar that is used as a part of the tip of the pencil shown in Figure 1.

In general, my pencil comprises a barrel 1, a tip 2 that is removably secured to the barrel for operatively holding the marking lead, and mechanism 3 for operatively advancing the lead through the tip 2.

The barrel 1 is of straight tubular form having internal screw threads that are adapted to cooperate with the lead-advancing mechanism and by means of which the tip 2 is removably secured to the barrel. The screw threads are cut away in the upper end of the pencil in order to provide additional space for a lead-containing magazine to be later described. The extreme upper end of the barrel has a ring 4 formed thereon which gives a neat and artistic appearance to the pencil.

The pencil tip 2 is formed with a tapered

bore 10 that extends from the mouth of a lead-receiving tube 11 to the open lower end of the tip. The lower portion of the tip 2 has pair of hair slits 12 that provide a spring clutch which grips the lead to prevent its movement through the pencil tip except when advanced by a suitable plunger to be later described. The portion of the bore 10 above the split portion of the tip is slightly larger than the marking lead to be used in the pencil whereas the mouth of the tip, which constitutes the spring clutch, is of slightly less diameter than the marking lead. The lower portion of the tip is preferably made of steel or other spring metal.

A sleeve 15, which has an opening through which the lead-receiving tube 11 extends, is screwed or soldered into the upper end of the tip 2. The upper end 16 of the lead-receiving tube 11 is swaged to secure the same within the sleeve 15 and to provide an enlarged mouth for the tube. The upper portion of the tip is threaded for engagement with the internal threads of the pencil barrel.

The operating mechanism of the pencil, which is most clearly shown in Fig. 2, comprises a plunger 20 that extends from a threaded operating nut 21 which engages the interior threads of the pencil barrel to effect the reciprocating movement of the plunger 20. The opposite sides of the nut 21 are grooved to receive a pair of arms 22 that are secured to a lead-containing magazine 23. The arms 22 have a centering sleeve 24 at their lower ends which acts as a guide for the plunger 20 and which also greatly strengthens the arms 22. A shoulder 25 is formed on each of the arms for a purpose that will presently be apparent.

The lower portion 27 of the lead magazine is of reduced diameter and the arms 22 are rigidly secured thereto. A sleeve 28, which is rigidly secured within the barrel of the pencil by dowel pins 29 or other suitable means, is adapted to engage the shoulders 25 of the arms 22 to prevent the complete removal of the operating mechanism while permitting a partial exposure of the lead containing magazine. The operating mechanism is freely rotatable within the sleeve 28. The lower portions of the arms 22 are bowed outwardly to effect frictional engage-

ment with the sides of the barrel to prevent the movement of the operating mechanism except when purposely manipulated.

An eraser container 29^a, which carries erasing material 30 is threaded into the mouth of the lead magazine and a cap 31 engages threads formed on the lead magazine.

Leads are removed from the magazine by holding the barrel of the pencil in one hand and pulling the cap longitudinally until a suitable portion of the magazine is exposed. The exposed portion of the magazine is then held and the cap and eraser are unscrewed to open the lead magazine. The shoulders 25, formed on the arms 22, engage the collar 28 that is secured within the barrel to prevent the exposure of more than the lead magazine, thereby protecting the operating mechanism from injury. This magazine, being of large cylindrical shape, carries an abundant supply of leads and provides a container from which the leads can be easily removed and in which there is no possibility of breaking the leads by reason of the bending of the container as is often the case where the leads are carried in tubes which also function as arms for operating the lead projecting mechanism.

The lead magazine is closed and the tip of the pencil is unscrewed from the barrel. The marking lead is dropped into the lead-receiving passage and the tip is again screwed into the barrel. This affords a very convenient and easy method of loading the pencil and has the advantage of not exposing the operating mechanism of the pencil to injury through careless handling.

Since the bore of the tube and the lead receiving passage that is formed in the tip of the pencil is only slightly greater than the size of the lead, there is no probability that lead of larger size than that intended for use in the pencil will be forced into the tube. The reinforcing collar 15 around the mouth 16 of the lead-receiving tube forms a very substantial mechanical protection against injury to the tube or the tip of the pencil through anything that might carelessly be done. The bending of lead-receiving tubes is a common source of injury to pencils now being manufactured.

With my construction, short leads may be completely used up. When leads are forced back through the lead-receiving tube in the reverse direction from that in which they are fed through such tubes, they are often broken and require considerable care in reloading. These difficulties are avoided in my pencil since the leads are merely dropped into the open end of the lead-receiving tube and are not forced through any restricted opening.

The lead is operatively supplied to the tip of the pencil by manipulating the cap

which, in turn, rotates the arms 22 which carry the nut 21 between them. This rotation of the nut advances and retracts the plunger 20 and thus advances the leads to the desired degree. The outward bow of the operating arms imposes sufficient resistance to the movement of the operating mechanism to prevent its accidental or unexpected operation.

The marked advantages of having relatively large operating parts cannot be over emphasized. Such operating mechanism is less costly to manufacture than the delicate mechanisms employed in many of the commercial pencils. The mechanism of my pencil will readily accommodate itself to the small graceful lines of the dainty pencils for ladies' use or readily adapts itself to the larger and more rugged design that is commonly desired by men. Such a mechanism also renders the pencil substantially fool proof, and, since the internal mechanism is positively protected against tampering by the user of the pencil, there is little or no likelihood that any injury can accidentally result from any reasonable service to which the pencil is subjected. The use of the special spring clutch, that is formed in the tip of the pencil, prevents breaking the point of the lead. This is a usual complaint where internal teeth or other mechanism is employed to prevent the lead from dropping out of the tip since such mechanism cuts into the lead and forms only a single fulcrum point instead of the large supporting area adjacent the exposed lead that my pencil provides. By forming the tip of highly resilient metal, any degree of clutch action can be obtained and furthermore, the weight of the tip of the pencil provides a proper balance that is a desirable feature.

Although I have illustrated and described a single application of my invention, I desire to fully protect all patentable novelty appearing therein and I desire, therefore, that only such limitations shall be imposed as are indicated by the spirit and scope of the appended claims.

What I claim is:

1. An automatic pencil comprising a barrel having internal screw threads over a portion thereof, lead advancing mechanism mounted within the barrel comprising, a cylindrical lead magazine, a pair of substantially parallel arms extending longitudinally from the magazine and terminating in a collar, a lead follower having threaded engagement with said barrel, said follower being mounted between said arms for reciprocating movement, and a pair of oppositely disposed shoulders formed on the outside of said parallel arms, a collar secured within said barrel and adapted to engage said shoulders to prevent complete longitudinal with- 115 120 125 130

drawal of said mechanism, and a removable tip secured to said barrel.

2. An automatic pencil comprising a barrel having internal screw threads over a portion thereof, lead advancing mechanism mounted within the barrel comprising, a cylindrical lead magazine, a pair of substantially parallel arms extending longitudinally from the magazine, and terminating in a collar, a lead follower having threaded engagement with said barrel, said follower being mounted between said arms for reciprocating movement, and a pair of oppositely disposed shoulders formed on the outside of said parallel arms, and a collar secured within said barrel and adapted to engage said shoulders to prevent complete longitudinal withdrawal of said mechanism, and a removable tip secured to said barrel, and comprising a body portion, a collar secured within the body portion, and a lead-receiving tube extending partially through the tip and completely through the collar, the upper

end of the tube being expanded to form a flared opening.

3. An automatic pencil comprising a barrel, a plunger reciprocably mounted within the barrel, means for actuating the plunger, a magazine for marking leads constituting a part of the actuating means, said magazine being adapted to be drawn longitudinally from the pencil to expose a portion thereof, and means independent of the plunger adapted to prevent the complete removal of said magazine.

4. An automatic pencil comprising a barrel, a lead magazine mounted within the barrel, a pair of arms rigidly attached to said lead magazine, a lead projecting plunger operated by said arms, and a tip removably secured to the barrel and adapted to receive leads for loading the pencil when separated therefrom.

In witness whereof I have hereunto signed my name.

HERMAN C. SPINDLER.
